CLAIM

The ornamental design for a box for transporting boards, as shown and described.

DESCRIPTION

FIG. 1 is a perspective view of a box for transporting boards showing a first embodiment of our new design; FIG. 2 is a front elevation view of the first embodiment;

FIG. 3 is a rear elevation view of the first embodiment;

FIG. 4 is a left side elevation view of the first embodiment;

FIG. 5 is a right side elevation view of the first embodiment;

FIG. 6 is a top plan view of the first embodiment;

FIG. 7 is a bottom plan view of the first embodiment;

FIG. 8 is another perspective view of the box for transporting boards of the first embodiment;

FIG. 9 is a perspective view of a box for transporting boards showing a second embodiment of our new design;

FIG. 10 is a front elevation view of the second embodiment;

FIG. 11 is a rear elevation view of the second embodiment;

FIG. 12 is a left side elevation view of the second embodiment;

FIG. 13 is a right side elevation view of the second embodiment;

(Continued)

FIG. 14 is a top plan view of the second embodiment; FIG. 15 is a bottom plan view of the second embodiment; FIG. 16 is another perspective view of the box for transporting boards of the second embodiment; FIG. 17 is an enlarged view of a portion 17 of FIG. 1; FIG. 18 is an enlarged view of a portion 18 of FIG. 6; FIG. 19 is an enlarged view of a portion 19 of FIG. 7; FIG. 20 is an enlarged view of a portion 20 of FIG. 7; FIG. 21 is an enlarged view of a portion 21 of FIG. 8; FIG. 22 is an enlarged view of a portion 22 of FIG. 8; FIG. 23 is an enlarged view of a portion 23 of FIG. 9; FIG. 24 is an enlarged view of a portion 24 of FIG. 14; FIG. 25 is an enlarged view of a portion 25 of FIG. 15; FIG. 26 is an enlarged view of a portion 26 of FIG. 15; FIG. 27 is an enlarged view of a portion 27 of FIG. 16; and, FIG. 28 is an enlarged view of a portion 28 of FIG. 16. The broken lines shown in FIGS. 1, 6, 9, 14, 17, 18, 23 and 24 illustrate portions of the box for transporting boards and form no part of the claimed design.

The broken lines shown in FIGS. 1, 6-9, and 14-28 illustrate the boundaries of the enlarged views and form no part of the claimed design.

The dot-dash broken lines shown in FIGS. 1, 6, 9, 14, 17, 18 and 23-24 illustrate the boundaries of the claim and form no part of the claimed design.
